UNITED STATES PATENT OFFICE.

FRANK L. BARNARD, OF SAUGUS, MASSACHUSETTS.

MANDOLIN ATTACHMENT FOR PIANOS.

SPECIFICATION forming part of Letters Patent No. 727,261, dated May 5, 1903.

Application filed June 21, 1902. Serial No. 112,637. (No model.)

To all whom it may concern:

Be it known that I, FRANK L. BARNARD, a citizen of the United States, residing in Saugus, in the county of Essex and State of Massachusetts, have invented an Improvement in Mandolin Attachments for Pianos, of which the following description, in connection with the accompanying drawings, is a specification, like letters on the drawings representing like parts.

This invention relates to an attachment for upright pianos whereby the effect of a mandolin or like instrument may be obtained.

The invention has for its object to provide an attachment of the character specified which is simple, inexpensive, and highly efficient for the purpose specified and which can be applied in a minimum time and at a minimum expense to any style or make of upright piano. For this purpose I employ a plurality of pendants of rubber, felt, or other suitable material having metallic surfaces which are adapted to be brought into contact with the usual strings or scale-wires of the piano and connect the said pendants at their upper end in such manner as will permit them to be moved laterally with relation to one another, so that the individual pendants may be adjusted to the scale-wires of the particular make of piano. The adjustability of the pendants may be accomplished by connecting the individual pendants to a band or strip of elastic material, such as rubber, which can be stretched in a direction substantially at right angles to the pendants in order to bring the individual pendants into line with the particular wire or wires with which it is desired to coöperate. The elastic band may be cemented, tacked, or otherwise secured to the damper bar or rail now commonly employed in pianos and which is operated by the foot-pedal in a piano having three pedals, or the said bar may be operated by hand, as will be described. The damper bar or rail is normally elevated, so as to withdraw the pendants out of the path of movement of the hammers, but is adapted to be lowered by means of the foot or by hand, so as to bring the pendants into line with the hammers, to be forced thereby against the strings or scale-wires when a key is depressed. These and other

features of this invention will be pointed out in the claims at the end of this specification.

Figure 1 is a perspective view, with parts broken away, of an upright piano provided with a mandolin attachment embodying this invention; Fig. 2, a detail in elevation to be referred to; Fig. 3, a detail in section to be referred to; Fig. 4, a detail of the attachment, showing the pendants in their normal position; Figs. 5 and 6, sectional views of modifications to be referred to; and Figs. 7 and 8, modifications of the attachment to be referred to.

Referring to Figs. 1 to 4, inclusive, *a* represents an upright piano of any suitable or desired make. The piano *a* is provided with the usual strings or scale-wires *b*, which are run in an upright direction at various angles, according to the particular style or make of piano. The scale-wires *b* in accordance with this invention have coöperating with them an attachment or device with which the effects of a mandolin or like stringed instrument may be obtained, and this attachment or device may and preferably will be made as herein shown, it consisting of a plurality of pendants *c*, of rubber, felt, or other suitable material, which are secured to a strip or band *d*, of rubber or other suitable elastic material. In Figs. 1 to 4, inclusive, the pendants *c* are represented as made in one piece with the strip or band *d*, which may be accomplished by taking a piece of rubber of the desired width and cutting or dying out portions of the said piece to form the pendants. The pendants have attached to them near their lower end metallic pieces, buttons, or heads *e*, which are designed to be brought into contact with the scale-wires when the mandolin effect is to be obtained. The rubber strip or band *d* is cemented, tacked, or otherwise attached to a support, which may be the damper-bar *f*, usually employed in three-pedal pianos. The bar *f* may be supported at its opposite ends by suitable levers *g*, pivoted to the sides of the piano case or frame, and which are suitably connected with a pedal *h* in a manner well understood and now commonly employed in this class of pianos. In upright pianos the strings or scale-wires *b* are arranged or run in various ways, according to the particular

style or make of piano; but by means of the band or strip *d* being elastic a workman can adjust each pendant in proper position with relation to the wire or wires with which the particular pendant coöperates, and it can readily be seen that this adjustment can be effected in a minimum time and with a minimum amount of labor, as the pendants are attached to the band or strip and require no handling, thereby leaving the operator free to stretch the band or not, as the occasion demands, and to tack or cement it to the bar *f* at the proper place.

In Fig. 4 the device or attachment is shown in its detached condition, in which it will be noticed that the pendants are separated substantially equal distances apart.

In Fig. 2 I have represented the device as applied in operative position, and by an inspection of said figure it will be seen that the third pendant from the left is separated by a substantially wide space from the second pendant and by a narrower space from the fourth pendant and that by so spacing the pendants the metallic heads or buttons are arranged in proper relation to the particular scale-wires with which they coöperate.

Normally the bar *f* and the attachment or device secured thereto are elevated above the path of movement of the hammers *i*; but when the mandolin effect is desired the attachment is lowered into substantially the position shown in Fig. 3, so that the metal portions or heads *e* are below the path of movement of the hammers, which strike against the pendants above the metal heads.

In pianos provided with only two pedals the attachment-support may be raised and lowered by hand, which may be effected as shown in Fig. 5 or as shown in Fig. 6. In Fig. 5 the lever *g* is normally held elevated by a spring *j* and may be turned on its pivot to lower the attachment by a cord or chain *k*, extended outside of the piano-casing and secured by a pin or projection *l*. In Fig. 6 the lever *g* is turned against the action of the spring *j* by pulling out a rod *m*, extended through the piano-casing and attached to one arm of an elbow-lever *n*, having its other arm connected by a link *o* with the lever *g*.

The pendants *c*, as shown in Figs. 2 and 4, are made in one piece with the elastic band or strip *d*; but I do not desire to limit my invention in this respect, as the pendants may be made separate from the band *d* and ce-

mented or otherwise secured to the said band, as shown in Figs. 7 and 8. In this case the pendants may be made of felt, leather, or other suitable material. By having the pendants attached to the elastic band the band 60 may be inclined at certain portions of its length, if required, in order to conform to the position of the hammers in relation to the scale-wires. The damper bar or rail *f* is now commonly found in nearly every three- 65 pedal piano, and in pianos not having a damper bar or rail the latter can be easily supplied.

I claim—

1. The combination with an upright piano 70 having scale-wires and a damper-bar movable with relation to said wires, of a mandolin attachment secured to said damper-bar and consisting of a plurality of pendants having metallic portions adapted to make contact 75 with said wires, and an elastic medium extended substantially at right angles to said pendants and connecting them together, substantially as and for the purpose specified.

2. A mandolin attachment for upright pianos, consisting of a strip or band of elastic material and a plurality of pendants firmly secured at one end to said strip or band intermediate of the ends of the same and extended substantially at right angles thereto, 85 and metallic portions secured to said pendants near their free end, substantially as described.

3. A mandolin attachment for upright pianos, consisting of a strip or band of rubber 90 or like elastic material, and a plurality of pendants of rubber or like elastic material integral with said strip or band and having metallic pieces secured to them, substantially as described.

4. A mandolin attachment for upright pianos, consisting of a strip or band of elastic material and a plurality of pendants firmly secured at one end to said strip or band intermediate of the ends of the same and extended substantially at right angles thereto, 95 substantially as described.

In testimony whereof I have signed my name to this specification in the presence of two subscribing witnesses.

FRANK L. BARNARD
